VEGETABLE CLEANING MACHINE

Samuel Olson, Chicago, Ill.

Application August 18, 1941, Serial No. 407,309

9 Claims. (Cl. 146—202)

This invention relates to a machine for cleansing fruits or vegetables, especially those of the type which grow in the ground, such as potatoes, and which therefore have a considerable quantity of earth clinging to them which must be removed to render them attractive for market.

One object of the invention is to provide a machine for removing the dirt from the vegetables without bruising them or otherwise injuring the surfaces thereof.

Another object is to provide a rotary cleaning chamber in which substantially the entire inner surface of the chamber consists of the yielding bristles of rotary brushes, which are thus kept in constant motion for scrubbing and polishing the surfaces of the vegetables in the chamber.

A further object of the invention is to provide means for polishing the cleansed surfaces and eliminating excess moisture therefrom.

It is also an object of the invention to provide a cleansing chamber having a portion of its interior surface lined with resilient material onto which the vegetables are initially delivered, and which avoids bruising them upon impact incident to such delivery.

The invention thus consists in certain features and elements of construction in combination, as herein shown and described and as indicated by the claims.

In the drawings:

Figure 1 is principally a vertical sectional view of a machine embodying this invention, but with the upper portion including a driving motor shown in side elevation.

Figure 2 is an end elevation of the machine showing the driving means for rotating drum or tumbling barrel and also the driving means for the rotary brushes thereof.

Figure 3 is a transverse vertical section taken substantially as indicated at line 3—3 on Figure 1.

Figures 4 and 5 are enlarged detail sectional views of the bearings for the rotary brushes together with adjacent structure.

The machine embodying this invention is in the nature of a hollow drum mounted for rotation upon a slightly inclined axis so that vegetables may be fed into the upper end of the drum and will gravitate toward the lower end for delivery therefrom after the cleaning and polishing operations have been performed in the drum. The upper end portion of the drum includes a sheet metal shell 1 with an internal lining 2 of resilient rubber or like material onto

which the vegetables may be delivered by hand or from a chute or conveyor, not shown, in any convenient manner. Extending through the cylinder 1 and also through the remainder of the machine there is shown a feed pipe 3 for water or other cleansing liquid, said pipe being fitted with discharge spray nozzles 4 disposed at convenient intervals within the drum.

Adjoining the cylindrical section 1, the second section of the drum is a perforated metallic cylinder 5 of somewhat larger diameter than the section 1 so as to encompass a series of cylindrical brushes 6 which are journaled parallel to the axis of the drum and in a circular series at intervals which render the brushes substantially contiguous. The inwardly projecting bristles of the brushes thus form the inner surface of the drum within the cylinder 5, and this surface is in approximate alignment with the rubber-lined surface of the cylinder 1 so that the vegetables pass from the upper cylinder to the adjacent lower one without substantial shock. Adjoining the cylinder 5 is a terminal cylinder 7 which is also of perforated sheet metal, and which is of such a diameter that its inner surface is substantially aligned with the surface formed by the bristles of the brushes 6, thus allowing the vegetables to roll or slide easily from the brushes onto the perforated section 7, which will provide for a final draining of the moisture from them before they are delivered from the machine.

As a matter of construction, it may be noted that the ends of the perforated cylinder 5 are secured to rings 8 and 9 of angular cross-section, while additional angular rings 10 and 11 are attached respectively to the rings 8 and 9 and project in opposite directions for connection with the cylinder 1 and the cylinder 7. Bearings 12 for the shafts of the rotary brushes 6 are fixed in the lapping portions of the angular rings.

The drum is supported on a suitable frame 15 in which it is mounted for rotation upon bearing rollers 16, journaled in brackets attached to the frame adjacent its ends. Rotation of the drum is effected by means of a motor 17 mounted on an upper portion of the frame and connected by a suitable gear reduction and drive chain 18 to a cross-shaft 19 having a bevel pinion 20 which meshes with a bevel ring gear 21 secured to the upper end of the cylinder 1. Each of the brushes 6 is provided with a shaft 22 and the upper end of the shaft is fitted with a sprocket 23 disposed outside the end of the main cylinder 5 so that the sprockets 23 are arranged

in a circular series encompassing the adjacent portion of the end cylinder 1.

A sprocket chain 24 is suspended by its ends from the side members of the frame 15 as seen in Figure 2, and forms a track on which the sprocket wheels 23 roll as the drum rotates and with which said wheels mesh so as to positively drive the rollers which constitute the lower portion of the drum at any given moment, and which thus support and contact with the vegetables which are passing through it for cleansing. As the rollers traverse the upper half of their circuit incident to rotation of the drum they pass out of mesh with the chain 24 and do not necessarily turn, but during this portion of their travel they are out of contact with the vegetables and are hence inactive.

The perforated wall of the cylinder 5 allows the water discharged from the spray nozzles 4 to escape and carry with it most of the dirt and foreign matter removed from the vegetables by the spray and by the abrasive action of the brushes 6, the perforations in the cylinder being large enough to pass small chunks of dirt or stems without clogging. This material is caught in a trough 25 which may extend under the entire length of the rotary drum, and which has a discharge conduit 26 leading from the lowest portion of the trough into a settling tank 27 mounted in the lower portion of the frame 15. In some situations the settling tank may be dispensed with, but where it is objectionable to discharge the muddy water directly into the sewer, the tank 27 is provided and includes a screw conveyor 28 rotatively mounted on an inclined axis in a fitted trough 29 which forms the bottom of the settling tank. Thus the solid matter which accumulates in the tank 27 and gravitates into the trough 29 is conveyed upwardly by the screw 28 and discharged at a special outlet 30 where it may be caught in a removable receptacle and carted away at intervals. A drain plug 31 at the lower end of the trough 29 provides for occasional flushing of this equipment. The water which accumulates in the tank 27 may be pumped out to a convenient remote point of discharge by way of an outlet pipe 32, and in order to maintain a definite level within the tank an overflow pipe 33 is also fitted therein, as seen in Figure 1.

With this equipment the vegetables, such as potatoes, are first rolled about and agitated within the upper cylinder 1 in contact with the resilient lining 2, while the force of the sprays issuing from nozzles 4 serves to dislodge most of the dirt and other foreign matter clinging to them—this material being flushed downwardly along the inclined lower surface of the cylinder 1 and discharged between the brushes 6 and through the perforated wall of the cylinder 5. Then, as gravity carries the vegetables into the brush-lined cylinder 5, they are further scoured and polished by the rotary action of the brushes 6, all revolving in the same direction at their upper surfaces which come in contact with the vegetables. At the same time, additional sprays from the nozzle 4 directly above the vegetables complete the cleansing of their surfaces, and the frictional action of the brush bristles tends to polish them so that as they are finally discharged into the perforated terminal cylinder 7 the elimination of any excessive moisture on the surface is all that is required to complete preparation of the product for marketing, or packaging for shipment, if desired.

While there is shown and described herein certain specific structure embodying the invention, it will be manifest to those skilled in the art that various modifications and re-arrangements of the parts may be made without departing from the spirit and scope of the invention, and that the same is not limited to the particular form herein shown and described, except in so far as indicated by the appended claims.

I claim as my invention:

1. A vegetable cleaner comprising a drum open at both ends, means supporting it for rotation about an inclined axis, rotary brushes mounted inside the drum in substantially contiguous relation to each other and with their axes extending parallel to the axis of the drum, and means by which said brushes are rotated all in the same direction by the rotation of the drum on its axis.

2. A vegetable cleaner comprising a drum open at both ends, means supporting it for rotation about an inclined axis, a portion of said drum being perforated with rotary brushes mounted inside said perforated portion in substantially contiguous relation to each other and with their axes extending parallel to the axis of the drum, means by which said brushes are rotated all in the same direction by the rotation of the drum on its axis, and a spray nozzle positioned inside the drum to discharge a cleansing liquid downwardly therein toward the brushes.

3. A vegetable cleaner comprising a drum open at both ends, means supporting said drum for rotation about an inclined axis, rotary brushes mounted inside the drum in substantially contiguous relation to each other and thus constituting substantially the entire supporting surface for vegetables in that portion of the length of the drum which said brushes occupy, and means for rotating said brushes while the drum rotates on its axis, the portions of the rotating brushes which face the axis of the drum moving in the same general direction as the drum, and relatively thereto.

4. A vegetable cleaner comprising a drum in the nature of a tumbling barrel open at both ends and mounted for rotation about an inclined axis, said drum having its inner wall surface at the upper end portion of the drum composed of resilient cushioning material, and rotary brushes mounted inside an adjacent portion of the drum in substantially contiguous relation to each other and with their axes extending parallel to the axis of the drum, said brushes thus constituting substantially the entire supporting surface for vegetables in that portion of the length of the drum and said supporting surface thus formed by the brushes being in approximate alignment with the resilient surface of the upper portion of the drum, and means by which said brushes are rotated all in the same direction by the rotation of the drum on its axis.

5. A vegetable cleaner comprising a drum open at both ends, means supporting it for rotation about an inclined axis, the upper portion of said drum being interiorly lined with resilient material, an intermediate section of the drum enclosing rotary brushes mounted in substantially contiguous relation to each other and with their axes extending parallel to the axis of the drum, a spray device supported inside the drum to discharge a washing liquid onto the vegetables therein, said drum including a lower end section beyond the portion which encloses the brushes, said brush-enclosing portion and said end section being of perforated material for draining the wash-

ing liquid, and means by which the brushes are rotated all in the same direction by the rotation of the drum on its axis.

6. A vegetable cleaner comprising a drum open at both ends, means supporting it for rotation about an inclined axis including an upwardly concave track, rotary brushes mounted inside the drum in substantially contiguous relation to each other and with their axes extending parallel to the axis of the drum, wheels attached to said brushes and positioned to ride on said concave track whereby said wheels contribute to the support of the drum and are driven to rotate the brushes as the drum rotates on its axis.

7. A vegetable cleaner comprising a drum open at both ends, means supporting the drum for rotation about an inclined axis, rotary brushes forming a portion of the interior surface of the drum, an upwardly concave track disposed in coaxial relation to the drum, and wheels attached to said brushes and positioned to engage said concave track to drive the brushes as the drum rotates, said track being formed to engage and drive only the wheels at the lower side of the drum.

8. A vegetable cleaner comprising a drum open at both ends, means supporting the drum for rotation about an inclined axis, rotary brushes forming a portion of the interior surface of the drum, an upwardly concave sprocket chain form-

ing a track disposed in co-axial relation to the drum, and sprocket wheels attached to said brushes and positioned to mesh with said chain to drive the rollers as the drum rotates, said chain extending to engage and drive only the wheels at the lower side of the drum.

9. A vegetable cleaner comprising a drum open at both ends, means supporting it for rotation about an inclined axis, the upper portion of said drum being interiorly lined with a resilient material, an adjacent section of the drum having openings in its wall with rotary brushes mounted inside the drum in substantially contiguous relation to each other and with their axes extending parallel to the axis of the drum, means by which said brushes are rotated by the rotation of the drum on its axis, a spray nozzle positioned inside the drum to discharge a cleansing liquid downwardly therein toward the brushes, a drain pan disposed under the perforated portion of the drum to receive the liquid and dirt discharged therefrom, and a settling tank into which said drain pan discharges including an upwardly inclined trough at the bottom of said settling tank with a conveyor in said trough for elevating and separately discharging solid matter which settles therein.

SAMUEL OLSON.
